UNITED STATES PATENT OFFICE

THOMAS E. FLAKE, OF BRECKENRIDGE, TEXAS, ASSIGNOR OF ONE-HALF TO CHARLES H. BROWN, OF BRECKENRIDGE, TEXAS

STUFFING BOX

Application filed June 18, 1928. Serial No. 286,119.

This invention relates to improvements in stuffing boxes, and it consists of the constructions, combinations and arrangements herein described and claimed.

5 An object of the invention is to provide a stuffing box of especial value when used in connection with oil or other wells employing a pumping jack and a polished rod, for which purpose the stuffing box is laterally yieldable so that it will adapt itself to the bend of the polished rod and will avoid the wearing of the bore in the packing into an oval shape.

10 Another object of the invention is to provide means whereby a cooling medium may be circulated above the packing in a stuffing box, so that the packing and the polished rod are prevented from becoming unduly heated as when the well has been pumped dry.

15 A further object of the invention is to provide a stuffing box in which the packing is readily removed and replaced, said means also being capable of employment to protect the packing as when the load of the rod string must be imposed upon the stuffing box, for 20 instance when the walking beam breaks.

25 Other objects and advantages appear in the following specification, reference being had to the accompanying drawing in which

30 Figure 1 is a vertical section of the improved stuffing box,

35 Figure 2 is a detail perspective view of the stuffing box, the handles being shown extended as in the act of tightening the packing,

40 Figure 3 is a cross section taken on the line 3-3 of Figure 1,

45 Figure 4 is a detail vertical section taken on the line 4-4 of Figure 2,

50 Figure 5 is a detail sectional view of one end of the opposing flanges, showing the washer turned over into a position to keep a load from the packing as later explained.

55 Those who are familiar with the pumping of oil wells are acquainted with the characteristic pumping jack which comprises, among other things, a walking beam and an adjuster box from which a polished rod is suspended. Usually the oil is pumped into tanks that set higher than the point of de-

livery at the well and it is therefore necessary to provide a stuffing box in which the polished rod works.

The end of the walking beam swings through an arc of a circle, and inasmuch as 55 considerable side movement is imparted to the polished rod the packing in the stuffing box wears readily on two sides, causing the bore in the packing to assume an oval shape. Room is thus afforded for the oil to leak out, 60 and much valuable fluid is thus lost. This condition is remedied by making the stuffing box laterally yieldable so that it can sway with the polished rod in its bending movements. 65

Another difficulty in the pumping of an oil well results when the well runs dry. Continued operation of the pumping apparatus will cause the packing to burn out, due to the 70 lack of lubrication of the polished rod in the packing. This condition is remedied by circulating a cooling medium through the stuffing box.

75 Further difficulties are encountered in practice when a breakage in the pumping apparatus occurs. At such times the weight of the load, comprising the rod string and the pump plunger at the bottom of the well, would have to be imposed on the stuffing box 80 while repairs were being made. This ruins the packing, but in order to prevent this, provision is made for relieving the packing of the load, the weight being imposed on more solid and rigid parts of the stuffing box. The use of the same means makes it easy to remove the packing from the stuffing box. All 85 these features will be understood from the drawing to which attention is now directed.

90 The familiar polished rod is indicated at 1. The upper end is connectible with a walking beam and the lower end with a string of rods that carry a pump plunger at the bottom of the well. None of these parts are shown because they are not essential to the invention. 95 The polished rod mentioned is subject to bending movements during the pumping operation, and for that reason the gland casting generally designated 2 and appearing above the broken line 4 is made subject to 100

lateral yielding so that the swaying of the polished rod may be compensated for.

A coupling 5 provides for the discharge of oil from the well tubing. One element 6 of a known stuffing box is screwed into the coupling 5, a sleeve or gland 7 of this element having a loose fit at 3 in the lower extremity of a collar 8 which is one of the parts of the invention. This collar has a flange 9 confronting a flange 10 on the element 6, the two flanges being of characteristic shape as seen in Figure 2.

Bolts 11 pass through the flanges and hold them together, but the fit between the flanges 15 is loose so that the gland casing 2 can swing or sway in respect to the element 6 without breaking any of the connections. Washers 12 are fitted upon the bolts between the flanges. A rib 13 is so placed on each washer 20 that it fits down over the edge of the flange 10 thus to leave a space 14 between the top of each lug and the bottom of the adjacent flange 9 while the pumping operation is going on. The space 14, together with the loose fit of the gland 7 in the collar 8 provides for the swaying of the gland projection.

A packing composed of a plurality of rubber or other suitable rings 15 adjacent to the gland end 7, and a plurality of rubber rings 30 16 separated from the rings 15 by a metal ring 17, occupies the bore 18 of the collar 8. The packing is followed by a gland 19 which is held down by a cap 20 that screws upon the sleeve 8 as at 21. The head 22 of the cap 35 is made hollow to provide a chamber 23 in which fluid may collect. This provision adds a measure of safety, insuring the prevention of the packing from burning out should the cooling system fail for any reason. The flanges 24, which form parts of the head, have large holes through which the polished rod 40 passes.

One of these flanges presses upon the gland 19, and ordinarily there would be a tight contacting surface between the flange and the end of the gland. Side extensions 25 of the head are so formed as to receive the enlarged ends of handles 26. These handles will ordinarily gravitate to the position shown in Figure 1 when released, but when the occasion arises to tighten the packing they will be swung up into the extended positions shown in Figure 2 where they are taken hold of to turn the cap 20. The handles swing in the extensions 25 as on a hinge.

Pipe connections 27 and 28, the former having a valve 29, are screwed into the collar 8 which has passages 30 with which the pipes communicate. Water is used as the cooling medium, and in order that it may reach the polished rod the gland 19 has a number of holes 31. The interior of the cap 20 as well as portions of the interior of the collar 8 form a chamber which will hold a considerable volume of water. It has been found that

water circulation very materially lengthens the life of the polished rod, especially when the well is running salt water with the oil, the effect of the circulating water being to wash the polished rod and thus retard 70 corrosion.

As has been indicated already, the washers 12 will be placed in such positions that the ribs 13 extend downward, the ends of the flange 10 fitting in the recess, as it were, formed between the washers and the flange. Should a breakage of the walking beam or other part of the pumping apparatus occur, so that the weight of the polished rod and its appurtenances would have to be imposed 80 upon the stuffing box, the washers 12 would be turned over into the position shown in Figure 5, thus to fill the space between the flanges 9 and 10 and relieve the packing 15, 16 of the weight. This prevents ruining the packing. 85

Should it become necessary to remove the packing the washers 12 will be removed from between the flanges 9 and 10 so that the weight of the gland casing 2 may be imposed upon the packing 15, 16. Upon removing the gland 19 and cap 20 the gland 7 will operate to push up on the rubber rings so that the first rings are readily gotten at. The washers 12 thus have several functions, namely, they permit the swaying movement of the 95 gland projection, prevent the imposition of weight upon the packing when turned in the position shown in Figure 5, and when removed, permit the pushing up of the packing 90 so that the first rings are readily taken out. 100

The operation

is readily understood. The working position of the improved stuffing box is as shown in Figures 1 and 4. The packing 15, 16 bears directly on the end of the gland 7. The latter is loose in the bore 18 of the collar 8, and as the polished rod 1 bends from side to side as the end of the walking beam traverses the arc of a circle, the gland casing 2 will sway 110 with the polished rod in respect to the rigid element 6.

Yielding of the rubber rings 15 and 16 will follow the sway of the gland projection, the rings alternately being compressed, then stretching. The resiliency of the packing on top of the gland projection 7 gives the stuffing box a hinge action. It may be explained here that it is not essential to use the metal 115 ring 17, but its use is desirable as a separator between the two systems of rubber rings.

As water circulates through the hollow cap 20 some of the water will reach the surface of the polished rod and work down into the 125 rubber rings where it will provide an excellent lubricant between the rubber and metal. The principal function of the cooling medium is to prevent over heating of the stuffing box when the well becomes pumped dry. The 130

chamber 23 will even take care of a case in which the cooling system fails.

Some of the water will work upward along the surface of the polished rod into the chamber 23 so that the chamber may become filled. Should the cooling system now fail, the water accumulated in the chamber 23 will work down again and so keep the parts lubricated at least to an extent where serious damage could not result. It is readily seen, without specific illustration, that the cooling medium can be introduced into the stuffing box at more than one point, in fact there is no particular limitation on the arrangement of the passages for the cooling medium. The purposes and advantages of the washers have been demonstrated already. The ordinary position is as shown in Figure 4, the space 14 providing the necessary looseness. The supporting position is shown in Figure 5, as when the polished rod 1 is let down so that certain repairs can be made. The removal of the washers has the effect of expelling the packing when the gland 19 and the cap 20 are released.

While the construction and arrangement of the improved stuffing box is that of a generally preferred form, obviously modifications and changes may be made without departing from the spirit of the invention or the scope of the claims.

I claim:—

1. A stuffing box comprising a fixed element with a gland, a gland casing loosely connected with said element, said gland casing comprising a collar having a bore in one end of which the gland has a loose fit, a cap attached to the collar having an associated gland extending into the other end of the bore with a relatively tight fit, and a resilient packing situated between the glands permitting relative swaying of the gland projection to compensate for bending movements of a polished rod operating in the stuffing box.

2. A stuffing box comprising a perforated rod gland, encasing means containing said gland having fluid intake and discharge passages for conducting a circulation of fluid through the encasing means to supply the perforations, and a chamber superimposed on the encasing means receiving a fluid seepage and providing a lubricant reservoir for the gland in the event of an interruption of fluid circulation through said encasing means.

3. A stuffing box comprising a rod packing a perforated rod gland resting on the packing, encasing means containing the packing and gland having intake and discharge passages conducting a circulation of fluid through the encasing means for supplying the perforations with fluid to lubricate the packing, said encasing means including a flange resting on the gland and providing a cover, and having a chamber above said flange, for receiving a seepage of fluid and providing a lubricant reservoir for the gland and packing in the

event of an interruption to the fluid circulation through the encasing means.

4. A stuffing box adaptable to a laterally swaying polished rod comprising a packing for the rod, an open-ended member by which the packing is contained, means carried by said member and operable therealong against the packing at one end of said member thus tending to expel the packing at the other end of said member, and a fixed rod gland independent of said member, upon which gland the other end of the packing rests to establish a centralized pivotal mounting for the superimposed member and its carried means.

5. A stuffing box for a laterally displaceable polished rod comprising a movable inverted open-ended member, a fixed, upright rod gland loosely extending into the open end of said member, there being a polished rod extending through said gland and member, and a rod packing in said member resting on the end of the gland to simultaneously provide a cushioned support for the movable open-ended member and to keep the packing under pressure through gravity.

6. In a stuffing box having a rod packing, an inverted open-ended member containing the packing, and a fixed rod gland engaging the packing at the open end of said member; confronting flanges respectively on the member and gland, a washer, and a rib on one flat face of the washer, said washer being reversible in position between the flanges first to contact the rib and the opposite face of the washer with the confronting surfaces of the respective flanges to fixedly support the member, second, upon reversal of the washer and the consequent emplacement of the rib in a position outside of said flanges, to space the member from said means and provide for free lateral play of the member, said washer standing in position to catch the member upon dropping thereby to prevent damage to the packing.
